UNITED STATES PATENT OFFICE.

CHARLES HOCKER, OF RUSHVILLE, INDIANA.

AUTOMATIC GATE FOR RAILWAY-CROSSINGS.

No. 830,788.

Specification of Letters Patent.

Patented Sept. 11, 1906.

Application filed February 24, 1906. Serial No. 302,756.

To all whom it may concern:

Be it known that I, CHARLES HOCKER, a citizen of the United States, residing at Rushville, in the county of Rush and State of Indiana, have invented a new and useful Automatic Gate for Railway-Crossings; and I do hereby declare the following to be a full, clear, and exact description of the invention, such as will enable others skilled in the art to 10 which it appertains to make and use the same.

The invention relates to crossing-gates for railways, and has for its object to provide a simple, durable, and inexpensive device of 15 this class which is adapted to be automatically operated by the passing train.

A further object of the invention is to provide a device of this character which will work smoothly and which will be to a great 20 extent noiseless.

With these and other objects in view the invention consists in the novel construction and arrangement of parts hereinafter described and shown, and particularly pointed 25 out in the appended claims.

In the drawings, Figure 1 is a plan view of a double-track railroad having my invention connected therewith. Fig. 2 is a side elevation of the gate with the trips only on one 30 side of the track. Fig. 3 is a longitudinal sectional view of one of the trips. Fig. 4 is a vertical section of the weight-frame and the gate-standard with the weight lowered. Fig. 5 is a front elevation of the weight-frame 35 with the weight elevated.

Referring more particularly to the drawings, 1 indicates a gate-standard to be supported upon one side of a road or street crossed by a railroad. Turning in brackets 40 31 on said standard 1 is a horizontal shaft 2, to which is rigidly secured the gate-arm 3. Also secured to the standard are buffers or leaf-springs 4, which are located in the path of an arm 5, extending laterally from the shaft 45 2 in a direction opposite the gate-arm, said arm being bifurcated at its free end and having a ball 6 pivoted on inturned ends of the members forming the bifurcation. This ball 6 is provided with a bore transverse to its 50 turning axis, and in this bore slides a link 7, having a head 8 at its upper end and pivoted at its lower end to a weight 9, to be hereinafter described. Surrounding this link 7 and abutting on the ball 6 at its upper end and a 55 flange 11 on the link at its lower end is a coil-spring 12, which serves as a cushion for trans-

mitting the motion of the weight 9 to the lateral arm 5, and consequently the gate-arm 3.

The weight 9, before mentioned, acts as a counterbalance for the gate-arm and is movable on vertical guides 13, positioned on a frame 14, mounted adjacent the gate-standard 1. Frame 14 has journaled thereon, one above the other, two shafts 15, each carrying a cam 16, both cams adapted to engage the 60 under surface of the weight 9, the weight being provided with a roller 17 to reduce the friction. Also connected with each shaft 15 is a vertical arm 18, to the opposite sides of which are pivoted links 19. To the lower 65 pairs of these links which extend in opposite directions parallel with the track nearer the gate are connected pull-bars 20, guided on rollers 21, mounted on brackets 22 along the track. At the other end of each pull-bar 20 70 is pivoted a link 23, which is connected to the lower end of an angled or double-armed lever 24, pivoted within a slot in a trip-frame 25, located adjacent the outside track a short 75 distance away from the crossing. This lever 24 carries a roller 26 at its upper end, said roller bearing on the under surface of a curved bar 27, projecting intermediate its ends through the slatted frame 25, pivoted at one end to the frame and having its other 80 end bent downwardly at an angle to the main portion, as at 28. This downward extension 28 is positioned within a U-shaped bracket 29, depending from the frame 25 and provided with a perforation in its bottom, in 85 which the extension works. A spring 30 surrounds the portion 28 and abuts on the lower portion of the bracket 29, this spring serving to return the bar 27 after it has been depressed in a manner hereinafter described. 90 The upper links 19 have the trips adjacent the opposite or second track connected thereto. For this purpose each link is pivoted to the end of an arm 33 on one end of a rock-shaft 34, which extends below both tracks 95 100 and has an arm 35 at its other end, a pull-bar 20 being connected thereto and to a trip in the same manner as to the trips adjacent the opposite or first-mentioned tracks.

Each train is provided with a trip-operating device, which is in the form of a roller 36, vertically adjustable in a U-shaped bracket 37 by means of a screw-rod 38, having connected therewith a bracket 39, in which the roller 36 is journaled. This roller should be mounted 105 on the engine in the rear and to one side of the fender, so that it may engage the

curved bars 27 of the trips, which are located on the outside of the tracks. Before the first trip is reached the roller 36 is lowered, and as the latter reaches the former it rides on its bar 27, depressing the same and causing the double-armed lever 24 to pull the bar 20, and consequently rotate one of the shafts 15. As a cam 16 is rigid therewith, it is also rotated or swung upwardly into engagement with roller 17 or weight 9, causing the weight to move upwardly and to transmit motion to the gate-arm 3 through coil-spring 12, which is compressed, and lateral arm 5. The gate-arm not having the weight to hold it elevated also has its own weight to assist it in closing, its lower movement being cushioned by the upper buffer 4 on standard 1. The cam 16 remains under the weight 9 until the train has passed the crossing, at which time the other trip on this side of the track is engaged. This trip causes the other pull-rod 20 to rotate the shaft 15 in the opposite direction and remove the cam from beneath the weight 9. The weight 9, together with the compressed spring 12, now causes the gate-arm to be elevated. A train on the other track will cause the same operation to take place.

Having thus described my invention, what I claim is—

- 30 1. The combination with the gate-arm, of a weight counterbalancing the same, a spring interposed in the connection between the weight and the gate-arm and placed under compression when the weight is elevated, and means controlled by the passing trains for elevating and then releasing the weight.
- 35 2. The combination with a standard, of a horizontal shaft journaled on the standard, a gate-arm secured to the shaft, a lateral arm extending from the shaft, a link connected to the arm, a weight to which the link is pivoted, a coil-spring surrounding the link and compressed when the weight is elevated, and means controlled by the passing trains for elevating and releasing the weight.
- 40 45 3. The combination with a standard, of a

horizontal shaft journaled on the standard, a gate-arm secured to the shaft, a lateral arm extending from the shaft, bifurcated at its outer end, a ball pivoted in the bifurcation and provided with a vertical bore, a headed link, fitted in the bore, a weight to which the link is pivoted, a spring placed under compression, when the weight is elevated, and means controlled by passing trains engaging 55 the weight to elevate it.

4. The combination with the gate-arm, of a weight counterbalancing the same, a pair of pivotally-mounted cams, for elevating and releasing the weight, and two pairs of trips, 60 each pair causing the elevation and the release of the weight through one of the cams.

5. The combination with the gate-arm, of a weight counterbalancing the same, a spring interposed in the connection between the 65 weight and the gate-arm, and placed under compression when the weight is elevated, and train-controlled cams for actuating said weight.

6. The combination of a gate-arm and a 70 weight, counterbalancing the same, a roller mounted on the lower portion of said weight, and upper and lower train-controlled cams adapted to engage said roller, substantially as described.

7. The combination with a standard, of a horizontal shaft journaled on said standard, a gate-arm secured to said shaft, a bifurcated lateral arm extending from the shaft, a ball pivoted in said bifurcation, and provided 80 with a vertical bore, a headed link mounted in said bore, and connected with a depending weight, said weight being provided with an antifriction-roller, and train-controlled cams engaging said roller.

In testimony whereof I have hereto affixed my signature in the presence of two witnesses.

CHARLES HOCKER.
